UNITED STATES PATENT OFFICE.

CHARLES A. MOLTANE, OF EL PASO, TEXAS.

POLISH-BOTTLE AND A COMBINED STOPPER AND DAUBER THEREFOR.

No. 892,284.

Specification of Letters Patent.

Patented June 30, 1908.

Application filed February 14, 1908. Serial No. 415,949.

To all whom it may concern:

Be it known that I, CHARLES A. MOLTANE, a citizen of the United States, residing at El Paso, in the county of El Paso and State of 5 Texas, have invented new and useful Improvements in Polish-Bottles and Combined Stoppers and Daubers Therefor, of which the following is a specification.

This invention relates to improvements in 10 bottles for liquid shoe polish and a combined stopper and dauber therefor, one object of the invention being to provide a combined stopper and dauber of simple construction by which the mouth of the bottle may be securely closed and the dauber readily removed for manipulation, and in which the dauber is provided with a handle adapted to lie in close contiguity to the bottle, so that 15 bottles filled with polish may be readily and compactly packed for storage or shipment.

A further object of the invention is to provide a novel construction of dauber in connection with a novel form of bottle, by which the blackening may be readily applied to the 20 dauber and the use of the entire contents of the bottle insured without liability of soiling the hands of the operator.

The invention consists of the features of construction, combination and arrangement 25 of parts hereinafter fully described and claimed, reference being had to the accompanying drawing, in which:—

Figure 1 is a longitudinal section through the polish bottle or receptacle, showing the 30 same closed by the improved dauber. Fig. 2 is a sectional plan view of the dauber shown in Fig. 1. Fig. 3 is a top plan view of a modified form of dauber. Fig. 4 is a side elevation of the same. Fig. 5 is a view similar to 35 Fig. 3 of another modified form of dauber.

Referring to the drawing, 1 designates a polish bottle or receptacle formed of glass or some other suitable material, said bottle or receptacle being designed to rest horizontally 40 upon its base or bottom wall and being provided in its top adjacent one end with a vertical opening or mouth 2, whose rim edge is horizontal and lies in a plane parallel with the top wall the front end wall of the bottle 45 below said mouth being curved upwardly and forwardly, as shown. This curved wall 3 permits the bottle to be tilted to dip the dauber into the polish when the latter is in a low level, thus permitting the entire con-

tents of the bottle to be used, as hereinafter 55 described.

The dauber comprises a body 4 of wood, cork or some other suitable material, said body being preferably of cylindrical form or suitably shaped at its lower end to snugly 60 fit within and close the mouth 2. A dauber proper 5, composed of cotton waste, sponge or other suitable absorbent material projects from the base of the body 4, and in the form shown in Fig. 1 is secured to the body 65 by a suitable fastening device, such as a staple 6. When the body 4 is in position to close the mouth 2 of the bottle, the dauber 5 depends into the body of the bottle and overhangs the curved wall 3, thus permitting the 70 bottle to be tilted in a forward direction, by which the body of polish may be brought into contact with the dauber, thus allowing the latter to be saturated before the withdrawal of the stopper. By this means the entire 75 contents of the bottle may be used, without the necessity of pouring out a small quantity left remaining, as in upright bottles of ordinary construction, under which operation the hands of the operator are liable to become 80 soiled. A handle 7 formed of a single piece of wire is provided for manipulating the dauber. The wire is doubled and bent in the form of an elongated loop 8 serving as a grip portion, then its portions are intertwined to 85 form a shank 8^a, and finally the free ends of the wire are bent to form a holding loop 8^b to encircle and fit within an annular groove 8^c in the body or stopper 4, the ends of the wire being suitably connected at the rear end 90 of the grip portion. It will thus be understood that the dauber may be conveniently applied and removed and manipulated in 95 polishing shoes, and by reference to Fig. 1 it will be seen that the handle 7 extends parallel with and close to the upper surface of the bottle, thus permitting the closed receptacle to be packed in convenient form for storage or transportation. It will be apparent that 100 this result is due primarily to the fact that the stopper fits vertically within the mouth and that the rim edge of the latter lies in a horizontal plane parallel with the outer surface of the top wall, thus allowing the handle extending at right angles from the stopper to 105 lie in close proximity to said wall and parallel therewith. The arrangement of the rim is also such that the adjacent portion of the

handle may contact therewith when the stopper is fully inserted, whereby the stopper is prevented from being inserted too far and the dauber 5 maintained in proper relation at all times to the curved wall 3.

In the construction shown in Figs. 3 and 4, the ends 9 of the wire forming the handle are bent at right angles and passed vertically down through the stopper and then bent laterally beneath the same, as at 10, to fasten the dauber 5, thus securing both the handle and the dauber to the stopper 4.

In the construction shown in Fig. 5, the ends of the wire pass straight through the dauber body and are then bent laterally, as at 11, in opposite directions to retain the same firmly in engagement.

The advantages of the invention will be readily understood from the foregoing description, and it will also be apparent that the bottle may be stood upright on the flat end opposite the curved end 3 without liability of leakage of the contents.

Having thus fully described the invention, what is claimed as new is:—

1. In a polish receptacle and combined dauber and stopper therefor, the combination of a receptacle having its greatest length in a horizontal plane and provided with horizontal top and bottom walls and a curved front wall, on which latter the receptacle is adapted to tilt, said receptacle being pro-

vided in its top wall above said curved front wall with a vertical mouth having its rim edge disposed in a horizontal plane parallel with said wall, a stopper for closing said mouth, a dauber upon the base of the stopper adapted when the latter is applied to overhang the curved wall, and a handle connected with the stopper and extending at right angles therefrom so as to lie close to and parallel with the top wall.

2. A combined dauber and stopper comprising a body, absorbent material at the lower end thereof, and a handle formed of wire having its free ends passed through the body and bent in opposite directions to lie against one of the faces of the body.

3. A combined dauber and stopper comprising a body, absorbent material at the lower end of the body, and a handle composed of a single piece of wire, said wire having its end portions passed downwardly through the body and bent in opposite directions against the underside thereof, said bent portions securing the absorbent material to the bottom portion of the body.

In testimony whereof I affix my signature in presence of two witnesses.

CHARLES A. MOLTANE.
